UNITED STATES PATENT OFFICE.

WALTER O. WHEELER, OF WORCESTER, MASSACHUSETTS.

STEAM-PUMP.

1,014,795.

Specification of Letters Patent. Patented Jan. 16, 1912.

Application filed September 24, 1909. Serial No. 519,481.

To all whom it may concern:

Be it known that I, WALTER O. WHEELER, a citizen of the United States, residing at Worcester, in the county of Worcester and Commonwealth of Massachusetts, have invented a new and useful Improvement in Steam-Pumps, of which the following is a specification, accompanied by drawings forming a part of the same, in which—

10 Figure 1 is a side elevation of a pump embodying my invention, and Fig. 2 is a central sectional view on the broken line 2—2, Fig. 1.

Similar reference characters refer to similar parts in the different figures.

15 The object of my present invention is to provide an automatic pumping apparatus adapted to maintain an automatic intermittent action by the alternate admission and 20 condensation of steam.

The apparatus forming the subject of my present invention is particularly adapted to be used in connection with steam radiators for the purpose of exhausting the air and 25 water of condensation therefrom, and my invention consists in the construction and arrangement of parts as hereinafter described and pointed out in the annexed claims.

30 Referring to the accompanying drawings, 1 denotes a fluid chamber having an inlet opening 2 connected with a steam radiator, or other chamber which it is desired to exhaust, and controlled by a valve 3 opening 35 inward to allow a free movement of air or liquid into the chamber 1, but preventing its return. The fluid chamber 1 is also provided with an exhaust or discharge opening 4 closed by a valve 5, which, opens outward 40 to allow the discharge of air or liquid from the fluid chamber 1. The fluid chamber 1 is provided with a cover 6, having a concentric bushing 7 to allow the free up and down movement of a sleeve 8 having its lower end 45 9 extending nearly to the bottom of the fluid chamber 1.

Attached to the upper end of the sleeve 8 is a shell 10 inclosing a condensing chamber 11, and provided on its outside with radial 50 ribs or fins 12. Passing through the bottom 13 of the fluid chamber 1 is a steam pipe 14, connected with some suitable source of steam supply and normally closed by a valve 15. The steam pipe 14 extends upwardly 55 through the sleeve 8 into the condensing chamber 11 with its upper end 16 terminating

near the top of the condensing chamber and provided with a cup shaped recess 17 containing a spherical valve 18, which normally closes by gravity the upper end of the steam pipe 14. The sleeve 8 is provided at its upper end with a flange 19 forming a tight joint with the bottom of the condensing chamber 11, and also with a flange 20 which is provided with knife edges 21, 21, which 60 rest in the notched bifurcated ends 22 of a lever 23 provided with a knife edge 24 supported upon a bracket 25 and forming the fulcrum for the lever 23.

65 Adjustable on the lever 23 is a counterweight 26, which is so placed on the lever that it will just counterbalance the shell 10 and hold it in a raised position. The lever 23 is connected by a link 27 with the steam valve 15, which is likewise held normally 70 closed by the counterweight 26. The bushing 7 is provided at the top with a cup shaped recess 28 to contain water for sealing the vertically movable sleeve 8. The sleeve 8 is also provided with a series of grooves 75 29, which fill with water and pack the joint between the movable sleeve 8 and the bushing 7.

A pipe 30 leads from near the bottom of the condensing chamber 11 to a spout 31 80 which empties into the cup shaped recess 28, and a pipe 32 leads from near the bottom of the exhaust opening 4 to the spout 31, said pipes being closed by spherical valves 33 and 33^a. Between the shell 10 and spout 31, the pipe 30 is provided with a telescopic section 34, which allows for the rising and falling movement of the shell 10 as hereinafter described. The cup shaped recess 28 is provided with an overflow pipe 85 35, through which any excess of water supplied through the spout 31 may be conducted away.

90 The apparatus is set in operation by removing a plug 36 and filling the fluid chamber with water until it lifts the valve 5 and escapes through the discharge opening 4, the water then standing upon the level indicated by the broken line 37. The end 38 of the lever 23 is then raised by hand in order to 100 open the steam valve 15, when steam passing through the pipe 14 fills the condensing chamber 11, driving out any air contained therein through the pipe 30. When the condensing chamber 11 has become filled with 105 steam, which may be determined either by a pressure gage or by the emission of steam 110

from said chamber, the lever 23 is released, allowing the counterweight 26 to descend and again close the steam valve 15 and maintain the condensing chamber 11 in the highest position. Condensation of the steam in the chamber 11 then takes place, hastened by the peripheral fins 12, thereby producing a partial vacuum in the chamber 11 and causing the water contained in the fluid chamber 1 to rise through the annular space between the steam pipe 14 and the sleeve 8 into the condensing chamber 11. As the water descends in the fluid chamber 1, a suction is created through the inlet opening 2, thereby maintaining a pressure upon the water in the fluid chamber until the water flowing into the condensing chamber has increased the weight of the latter in excess of the counterweight 26 when the shell 10 descends, rocking the lever 23 and opening the steam valve 15, thereby admitting steam to the condensing chamber 11 which forces the water in the condensing chamber back into the fluid chamber 1. If only air has been drawn into the fluid chamber through the inlet opening 2, it will escape through the pipe 32, but if the fluid chamber has filled with water through the inlet opening, it will be forced through the outlet opening 4, raising the valve 5 until the water level 37 is again reached. When the water has been forced from the condensing chamber 11, the latter will become lightened sufficiently to allow the counterweight 26 to reverse the action of the lever 23, thereby closing the steam valve 15 and raising the shell 10 to its normal position, when the condensation of steam again takes place and the pumping action is repeated. Resting upon the bottom of the shell 10 is a cup 39 which incloses the lower end of the pipe 30, and is raised by the inflowing water into the chamber 11 until the bottom of the cup is made to close the pipe 30. As the water continues to rise, it will fill the cup 39 causing it to fall upon the bottom of the shell 10, but, being filled with water, it will act as a seal to the pipe 30. The pipe 30, therefore, remains open for the escape of air during the initial entrance of steam, but subsequently becomes sealed by means of the cup 39. The pipe 32 has its lower end inclosed in a similar cup 40, which permits the escape of air past the valve 33 during the initial filling of the fluid chamber with water. After the cups 39 and 40 become filled with water, more or less of the water contained therein is liable to be forced through the pipes 30 and 32 and delivered by the spout 31 into the cup 28, thereby maintaining a water packing for the slideable sleeve 8. After the apparatus has once been put in operation, it will continue to work automatically, producing an intermittent suction

through the inlet opening 2 from a radiator, or other connected chamber, into the fluid chamber 1 and a discharge therefrom through the discharge opening 4. The water in the fluid chamber 1, when steam is admitted to the condensing chamber 11, will be forced upward into the condensing chamber until the combined weight of the shell 10 and the water contained therein is in excess of the counterweight 26, when the latter will be raised, opening the steam valve 15 and allowing the pressure of steam to again force the water from the condensing chamber 11 back into the fluid chamber 1, and causing any excess of water which may have been received in the fluid chamber 1 through the inlet opening 2 to be delivered through the discharge opening 4. The water remaining permanently in the fluid chamber 1, therefore, acts as a liquid piston which, by its rising and falling movement, sucks through the inlet opening 2 into the fluid chamber 1 and discharges the excess of water so received through the discharge opening 4.

I claim:

1. In an apparatus of the class described, a fluid chamber, valve controlled inlet and outlet passages thereto, a condensing chamber separate from said fluid chamber, a valve controlled steam admission pipe leading to said condensing chamber, a connecting pipe between said fluid chamber and said condensing chamber, and a predetermined amount of liquid in said fluid chamber arranged to close said connecting pipe.
2. In an apparatus of the class described, a fluid chamber, inlet and outlet passages communicating with the upper part of said chamber, check valves in said passages, a pivoted lever, a shell inclosing a steam condensing chamber supported on one end of said lever, with the bottom of said condensing chamber communicating with the top of said fluid chamber, a steam pipe leading from a source of steam supply to the upper part of said condensing chamber, and a valve closing said steam pipe and operatively connected with said pivoted lever.
3. In an apparatus of the class described, a fluid chamber arranged to be filled with liquid to a certain level, a condensing chamber separate from said fluid chamber and communicating therewith below said lever, a steam pipe leading to said condensing chamber, and means for opening and closing said steam pipe.
4. In an apparatus of the class described, a pumping chamber partially filled with liquid, a condensing chamber communicating with said fluid chamber below the level of said liquid, a steam passage leading from a source of steam supply to said condensing chamber, and automatic means for opening and closing said steam passage.

5. In an apparatus of the class described, a fluid chamber having valve controlled inlet and outlet openings, a cover for said chamber, a sleeve vertically movable in said 5 cover, a shell mounted on said sleeve and inclosing a condensing chamber, a counterweight for said shell, a steam pipe leading to said condensing chamber, a valve closing said steam pipe, and means for opening and 10 closing said valve controlled by the vertical movement of said shell.

6. In an apparatus of the class described, a fluid chamber having valve controlled inlet and outlet openings, a sleeve entering 15 said chamber from the top and capable of a vertically sliding movement, a shell mounted on said sleeve, a counterbalanced lever supporting the weight of said shell, a steam pipe leading to said shell, a valve closing 20 said pipe, and means operatively connected with said lever for opening said valve by the downward movement of said shell.

7. In an apparatus of the class described, a fluid chamber having valve controlled inlet and outlet passages, a sleeve vertically 25 slideable in the cover of said fluid chamber, a

shell inclosing a condensing chamber mounted on said sleeve, a lever supporting said shell on one end, an adjustable counterweight for said lever, a steam pipe concentric with said sleeve and entering said condensing chamber, a valve in said steam pipe and means connecting said valve and said lever, whereby the tilting motion of said lever will open or close said valve.

35

8. In an apparatus of the class described, a fluid chamber, a liquid contained therein, a steam condensing chamber above said fluid chamber communicating with said fluid chamber below the level of the liquid in 40 said chamber, alternate means for admitting steam to said condensing chamber and for condensing the steam admitted therein, whereby the level of the liquid in said fluid chamber is varied, and valve controlled inlet and outlet passages connected with said fluid chamber.
